RIVET HEADING TOOL FOR CHAIN SAWS

George A. Arnett, Wichita, and Lloyd T. Smith, Newton,
Kans., assignors to Rains Manufacturing Company,
Inc., Newton, Kans., a corporation of Kansas

Filed Sept. 5, 1961, Ser. No. 66,612

Term of patent 14 years

(Cl. D54—10)

Fig. 1.

Fig. 2.

Fig. 3.

Fig. 4.

FIG. 1 is a side elevational view of a rivet heading tool for chain saws, showing our new design.

FIG. 2 is an edge elevational view thereof;

FIG. 3 is an elevational view showing one end of the rivet heading tool for chain saws; and

FIG. 4 is an elevational view showing the opposite end of a rivet heading tool for chain saws.

We claim:

The ornamental design for a rivet heading tool for chain saws, as shown.
